UNITED STATES PATENT OFFICE.

LANSING ONDERDONK, OF NEW YORK, N. Y., ASSIGNOR TO UNION SPECIAL SEWING MACHINE CO., OF CHICAGO, ILLINOIS, A CORPORATION OF ILLINOIS.

FEEDING MECHANISM FOR SEWING-MACHINES.

No. 839,076.

Specification of Letters Patent.

Patented Dec. 18, 1906.

Application filed May 21, 1901, Serial No. 61,271.

To all whom it may concern:

Be it known that I, LANSING ONDERDONK, a citizen of the United States, residing at New York, in the county of New York, State of New York, have invented certain new and useful Improvements in Feeding Mechanism for Sewing-Machines, of which the following is a description, reference being had to the accompanying drawings and to the letters of reference marked thereon.

My invention relates to an improvement in sewing-machines, and particularly to a feeding mechanism therefor, the object being primarily to provide a feeding mechanism for post and post-cylinder machines of the type illustrated in my application for Letters Patent, filed of even date herewith, Serial No. 61,272.

The invention consists in the various matters hereinafter described and referred to in the appended claims.

In the accompanying drawings, which illustrate the invention, Figure 1 is a plan view of a sewing-machine illustrating my invention, portions being removed. Fig. 2 is a side elevation, the tubular bed-plate being in longitudinal vertical section. Fig. 3 is a transverse vertical section on the line 3 3 of Fig. 2. Fig. 4 is a front elevation of the main-feed-bar-operating lever. Figs. 5 and 6 are front and side elevations of the auxiliary-feed-bar-operating lever. Fig. 7 shows in detail the eccentrics for actuating the said two levers; and Fig. 8 is a detail perspective view of the feed and looper operating devices, the space separating the two mechanisms being exaggerated.

Briefly, the machine-frame comprises a hollow horizontal angular casing A, from the rear end of the member A' of which rises the gooseneck A², being the forward case member. At the left-hand end of the case member A² rises the hollow post A³, from the upper end of which projects the rearwardly-extending cylindrical bed-plate or horn A⁴, parallel with the case member, but in a higher plane.

The upper tension mechanism, the needle-bar N, the needle-clamp n, its operating-lever, the presser-foot P, and presser-bar P' are of usual construction and need not be further described.

The horizontal drive-shaft C is mounted in bearings in the frame and has two cranks c c, to which are connected the rear ends of the connecting-rods C' C', which at their opposite ends are connected with cranks d d on the right hand of the line-shaft D, mounted in bearings in the front case member A². The left-hand end of the line or driven shaft D is within the lower end of post A³, provided with two eccentrics d² d³, the former carrying a wrist-pin d⁴, upon which is mounted the looper-operating lever L', which at its upper end is connected in the manner shown to the sliding and locking looper-shaft L, carrying on its outer end the loopers l, this looper-operating lever having a pivotal connection with the sliding and oscillating looper-shaft and also having a sliding pivotal connection with a bearing-block pivoted to a fixed part of the machine-frame. These parts do not form a part of the present invention, but are claimed in an application filed by me of even date herewith.

F designates the four-motion feed-bar, mounted in bearing-blocks or guideways f f within the top of the cylindrical bed-plate A⁴ and carrying at its rear end the feed-dog F', the teeth of which project rearwardly or away from the operator, so as to feed the work off the cylindrical bed-plate or horn. The feed-bar F is pivotally connected at its rear or far end to vertically-disposed links f' f', pivoted at their lower ends in the lower portion of the bed-plate or horn A⁴, and the near or front end of the feed-bar—i. e., the end nearest the operator—is pivotally connected to the upper forked end f² of the main lever F², the lower end of said lever being strapped to the larger eccentric d² on the shaft D. The lever F² is further acted upon by the auxiliary lever F³, forked at its lower end f⁴ to straddle the smaller eccentric d³ of the shaft D and split thereabove, as at f¹⁰, and having a tightening-screw f¹¹ to regulate the space between the forks. This lever F³ is pivoted at its upper end to the right side of the lever F² by a pivot-screw f⁵, (shown in dotted lines, Fig. 3,) and the lever F² is further provided between its ends with a longitudinal fulcrum-slot f⁶, through which passes the enlarged rounded portion of the fulcrum-bolt f⁷, having a flattened threaded end

mounted adjustably in an inclined vertically-disposed slot a^8 in the post A^3 . (See Fig. 3.) By adjusting this bolt f^6 the throw of the feed-bar may be lengthened or shortened to vary the stitch.

It will be seen that the main lever F^2 affects the raising and lowering of the front end of the feed-bar and also raises the lever F^3 and that in the further rotation of the eccentrics d^2 d^3 the auxiliary lever F^3 will be rocked on its axis f^6 , so as to rock the main lever and impart the necessary longitudinal movement to the feed-bar F . The auxiliary lever F^3 forms, therefore, a sliding and oscillating pivot for the lever f^2 .

Having thus described my invention, what I claim as new, and desire to secure by Letters Patent, is—

1. A feeding mechanism for sewing-machines, comprising a driving-shaft, and means for rotating the same, eccentrics on said shaft, a longitudinally-extending feed-bar, a feed-dog thereon, a vertically-disposed feed-bar-operating lever connected at its lower end to one of said eccentrics, and extending into pivotal connection with the adjacent end of said feed-bar slidably pivoted between its ends to a stationary part of the machine-frame, an auxiliary lever connected at its lower end to the other of said eccentrics, and pivotally connected at its upper end to the main-feed-bar-operating lever near the upper end thereof; substantially as described.
2. The combination, with the angular casting comprising forward lower horizontal case member, the vertical member and the rearwardly-extending horn projecting from the upper end of said vertical member, of a line-shaft in said forward case member, means for rotating said shaft, eccentrics on the end of said shaft, within the lower end of said vertical case member, a feed-bar extending longitudinally in the horn and provided at its rear end with a feed-dog, a vertically-disposed feed-bar-operating lever connected at its lower end to one of said eccentrics, and upwardly through the vertical case member into pivotal connection with the adjacent end of said feed-bar, slidably pivoted between its ends in the vertical casing member, an auxiliary lever, connected at its lower end to the other of said eccentrics, and pivotally connected at its upper end to the main-feed-

bar-operating lever near the upper end thereof; substantially as described. 55

3. The combination with the angular casting, comprising the forward lower horizontal member, a vertical member having a slot, and the rearwardly-extending horn projecting from the upper end of said vertical member, of a line-shaft in said forward case member, means for rotating said shaft, eccentrics on one end of the line-shaft within the lower end of said vertical case member, a feed-bar 60 extending longitudinally in the horn, and provided at its rear end with a feed-dog, a link pivoted at its lower end in the horn, and pivoted at its upper end to the feed-bar between the ends thereof, a vertically-disposed feed-bar-operating lever in the vertical case member, and connected at its lower end to one of said eccentrics, and at its upper end pivotally connected to the adjacent end of the feed-bar, an auxiliary lever, connected at 70 its lower end to the other of said eccentrics pivotally connected at its upper end to the feed-dog-operating lever near the upper end thereof, and slotted longitudinally between its ends, and a fulcrum-bolt having a rounded 75 portion extending through the slot in the auxiliary lever and a squared portion adjustable in the slot in the vertical case member; substantially as described.

4. A feeding mechanism for sewing-machines, comprising a driving-shaft, and means for rotating the same, eccentrics on said shaft, a longitudinally-extending feed-bar, a feed-dog thereon, a vertically-disposed feed-bar-operating lever connected at its 85 lower end to one of said eccentrics, and extending into pivotal connection with the adjacent end of said feed-bar slidably pivoted between its ends to a stationary part of the machine-frame, an auxiliary lever connected 90 at its lower end to the other of said eccentrics, and pivotally connected at its upper end to the main-feed-bar-operating lever near the upper end thereof, a pivotal support for said auxiliary lever and means for 95 adjusting said pivotal support on the machine-frame; substantially as described.

In testimony whereof I affix my signature in presence of two witnesses.

LANSING ONDERDONK.
